Inventor:
Arthur Prentiss

United States Patent Office.

ARTHUR PRENTISS, OF PRENTISS VALE, PENNSYLVANIA.

Letters Patent No. 64,798, dated May 14, 1867.

IMPROVED INHALER.

The Schedule referred to in these Letters Patent and making part of the same.

TO ALL WHOM IT MAY CONCERN:

Be it known that I, ARTHUR PRENTISS, of Prentiss Vale, McKean county, State of Pennsylvania, have invented new and useful improvements in Instruments for Medical Inhalation; and I do hereby declare the following to be a full and exact description of the same, reference being had to the drawings which accompany and form a part of these specifications, in which—

Figure I shows the article entire in one form of structure.

Figure II, view of the instrument of another form of structure, sectional.

Figure III, a sectional view of cap and stoppers at the large end.

Figure IV, sectional view cut in a line at P, showing guard cork placed in neck.

Figure V, view of small cup and mouth-piece, with cork to stop small end of the tube A.

Letter A, a small glass tube, and may be of the same diameter at both ends, or one end may be larger, as shown at 2. Letter B, sponge or other porous substance that will readily absorb liquids, the medicine being prepared in the liquid form. Letter C, circle of rubber lying at bottom of the cup E.

For the convenience of the pocket, or to carry in reticule or trunk, the stoppers E E, caps g g', and cords or chains i i are used to close each end of the tube A. The form shown in Fig. II may sometimes be more desirable, as affording opportunity to apply the medicine to the sponge while the instrument is in use; or, the glass may be larger in the centre, as shown by the figure in red lines, the sponge being forced in while dry, and the medicine poured in afterwards at one end. Persons needing inhalation, or those suffering from catarrh, inflammation of the fauces or tonsils, bronchial irritation or pulmonary tendency, are very often able to, and are, travelling about; hence a pocket inhaler, or one safely carried in valise or trunk, and possessing the property of being cleansed readily, would be of great value.

In constructing these implements I make the tube and stoppers plain, removing the stoppers when used; or, I form a groove or grooves in the stoppers, as seen in Figs. III and IV, so that, when said stoppers are partly drawn, the air may flow in around the large stopper, and be drawn out at the smaller end; or, a hole may be made in the end at O; and then it would only be necessary to turn the stopper partly around, or till one of the grooves in the cork comes in conjunction with the said opening O, and the air may enter this way; or, grooves partly in the stoppers and partly in the walls of the tube may be adopted as means of closing and opening the ends. The stoppers would be removed when it was desirable to inflate the lungs quickly, but left in when it was desired to inflate them slowly and by exertion. When the body of the implement is fashioned as in Fig. II the end for the mouth may be bent, as shown, or it may be left straight, and a bent mouth-piece inserted, as shown by the red lines in Fig. II. When the small cap g' is turned close the cork in it is pressed down on to another fixed firmly in the neck of the tube at m. For durability and hard usage the whole implement may be formed or made of metal, hard rubber, or other suitable material.

My invention relates to improvements in the manufacture of inhalers as to arrangement of parts, compactness, and portability, the latter property being such that the implement may be carried for days in the travelling-trunk, or in the pocket about the person, without removing the medicine, as it is corked as tight as though in a separate vial.

What I claim as my invention, and desire to secure by Letters Patent, is—

An inhaler, when formed and its various parts arranged substantially as described and for the purposes set forth.

ARTHUR PRENTISS.
